(57) **CLAIM**

The ornamental design for a fluid channel, as shown and described.

DESCRIPTION

FIG. 1 is a bottom, rear, left perspective view of a fluid channel;

FIG. 2 is an enlarged view of area 2 in FIG. 1;

FIG. 3 is a top view thereof;

FIG. 4 is a bottom view thereof;

FIG. 5 is an enlarged view of area 5 in FIG. 4;

FIG. 6 is a front view thereof;

FIG. 7 is a rear view thereof;

FIG. 8 is a left side view thereof; and,

FIG. 9 is a right side view thereof.

The short dash-long-dash broken lines in the drawings depict the boundaries of the claimed design and form no part of the claimed design.

The dot-dot-dash lines in the drawings depict the boundaries of the enlarged views and form no part of the claimed design.

The dashed lines and unshaded areas encompassed by the dashed lines depict portions of the fluid channel that form no part of the claimed design.
